UNITED STATES PATENT OFFICE.

THADDEUS W. HEERMANS, OF EVANSTON, AND NORMAN WHICHELLO,
OF CHICAGO, ILLINOIS, ASSIGNORS TO JOHN A. ROCHE, OF CHICAGO,
ILLINOIS.

ELECTRIC ELEVATOR.

SPECIFICATION forming part of Letters Patent No. 622,355, dated April 4, 1899.

Application filed January 29, 1898. Serial No. 668,453. (No model.)

To all whom it may concern:

Be it known that we, THADDEUS W. HEERMANS, a citizen of the United States, residing at Evanston, and NORMAN WHICHELLO, a subject of the Queen of Great Britain, residing at Chicago, in the county of Cook and State of Illinois, have invented a new and useful Electric Elevator, of which the following is a specification.

10 This invention relates to electric elevators, and particularly to means for controlling the circuits of the hoisting-motors.

15 The object of the invention is to provide mechanical means for positively gaging the rheostat or controller-arm.

20 Other objects of the invention will appear more fully hereinafter.

25 The invention consists, substantially, in the construction, combination, location, and relative arrangement of parts, all as will be more fully hereinafter set forth, as shown in the accompanying drawings, and finally specifically pointed out in the appended claims.

30 Referring to the accompanying drawings and to the various views and reference-signs appearing thereon, Figure 1 is a plan view of an electric elevator, showing the invention applied thereto. Fig. 2 is a broken detail view, in vertical section, on the line 2 2, Fig. 1, looking in the direction of the arrows and showing the arrangement of means for actuating the rheostat or controller-arm. Fig. 3 is a similar view on the line 3 3, Fig. 2, looking in the direction of the arrows. Fig. 4 is a detached detail view, in side elevation, parts broken away and parts in transverse section, showing the construction and arrangement of the invention.

35 The same part is designated by the same reference-sign wherever it occurs throughout the several views.

40 In the drawings, reference-sign A designates a suitable supporting base or frame, in which is suitably journaled the drum B, upon which is wound the car-hoisting cables.

45 C is a hoisting-motor, the shaft D of which is suitably geared to the axle of drum B for rotating the latter.

50 E is a brake-wheel for the motor-shaft, and F the braking means.

The parts so far described may be of any suitable ordinary or well-known construction and type, and inasmuch as the present invention does not reside in the specific construction and arrangement thereof we deem it unnecessary to more specifically illustrate or describe the same. 55

Suitably mounted and arranged are a series of contacts G for controlling the circuits to the motor C. 60

H is a contact-arm for successively making contact with the contacts G in order to control the circuits of the motor. It is evident that the contacts G may control resistances or they may alter the motor-circuit leads or 65 may successively cut in or out of the motor-circuit resistances or auxiliary coils. We shall therefore hereinafter refer to the arm H as the "controller-arm" irrespective of the particular operation of such arm in effecting 70 a controlling of the motor-circuits.

In the construction and arrangement of electric elevators it is exceedingly important to provide an arrangement wherein the controller-arm may be started at whatever position the hoisting motor-shaft may be and hence at whatever position the car may be. It is also important to provide means whereby the controller-arm is manipulated to perform its function when once started up, to the end 75 that the motor when started may quickly attain its desired speed by having the resistances included in the motor-circuit when it rests removed therefrom or by commutating the fields of the motor to effect the same purpose. It is also important that when the controller-arm is actuated to its fullest extent it will be held in such position during the subsequent operation of the motor and until the requirements of its actuation have been fulfilled, and thereafter it is important that provision be made for returning said arm to its 80 original or initial position. These desirable objects are obtained in the present construction and arrangement in the following manner: The arm H is pivotally mounted, as at 85 J, and the hub of said arm is provided with an abutment K. Suitably journaled in the framework and in proper relation to the controller-arm H is a shaft L. The series of arms 90

95

M are mounted eccentrically upon said shaft L and have their ends arranged under suitable conditions, hereinafter to be referred to, to engage the abutment K of the controller-arm H. In the particular form shown the shaft L carries a series of eccentric-disks N, and the arms M are in the form of straps, which receive the said disks N. The ends of said arms M are arranged to rest loosely in 10 the yoke O, carried at one end of a lever P, pivoted to a fixed support, as at Q, whereby when said lever P is rocked about its pivot the free ends of arms M may be raised to a position such as to clear the abutment K 15 or may be lowered into position for the free ends of the said arms to engage said abutment. The normal position of yoke O is such as to maintain the free ends of arms M in position to engage behind the abutment K, as 20 clearly shown. The limiting-stop R serves to adjustably regulate the position of the lever P. Any suitable or convenient means may be employed for rocking lever P. This may be accomplished by means of a connecting-rod S, as shown in Fig. 4, suitably actuated from the car by hand-cables or otherwise, or said lever P may be rocked by means 25 of a cam projection on the disk T, suitably mounted and operated by an auxiliary motor or other means controlled from the car, as 30 shown in Figs. 1, 2, and 3. This disk is provided in the periphery thereof with a notch U, arranged to be engaged by the end of a weighted arm V, carried by the lever W, pivotally supported at its upper end, as at 5, and out of vertical alinement with the periphery of disk T at a point where the end of arm V bears thereagainst, as clearly indicated 35 in Fig. 2. By this construction it will be seen that when disk T is rotated into suitable position with the notch U opposite the end of arm V the end of said arm will be carried by gravity into such notch, thereby locking the disk T against rotation. The lower end of 40 the lever W carries an adjustable set-screw 6, whereby the position of said arm V relative to the periphery of disk T may be regulated. The disengagement of arm V from notch U to enable disk T to be rotated may be 45 effected in any suitable or convenient manner, and when such disengagement is effected said disk may be rotated in any suitable or convenient manner by hand-cable or electrically from the car, whereby the cam projection 50 therein engages lever P and rocks the yoke or head O carried thereby to raise the ends of arms M out of engaging position with respect to the abutment K or lowers the same into engagement with such abutment. It 55 will be observed that the arms M are in close proximity to each other and that a large number of these arms are provided. It will also be seen that the position of each succeeding eccentric disk or crank connection N on shaft 60 L varies slightly from the position of the preceding disk or crank connection, whereby the succeeding arms M are not advanced or

projected endwise in unison with each other, but the limit of throw of each arm is attained a short space of time after the limit of throw 70 of the preceding arm has been attained, the variations depending on the variations in the relative positions of the eccentric disks or crank connections N on shaft L. The controller-arm H may be held normal in one limit 75 of its rocking motion in any suitable manner, as by means of weighted arm 7, as in Figs. 2 and 3, or by means of spring 8, as in Fig. 4.

The operation is as follows: Supposing the controller-arm to be in its normal limit of 80 rocking motion—that is, occupying a position therein, as indicated in Figs. 2 and 4—it will be observed that at least one of the arms M is always in position to engage behind the abutment K. Now suppose that it be desired 85 to actuate the controller-arm H. Rotation is imparted in any suitable or convenient manner to shaft L, the particular arm or arms M which, when the controller-arm H is in normal position, is in engagement behind abutment K, is advanced, thereby rocking controller-arm H so as to make successive connection with the contacts G. When the limit of throw of the initially-engaging arm M is attained, one or more of the succeeding arms 90 will have fallen into engaging position with respect to the abutment K, and thus the arm H is maintained in the opposite limit of its rocking motion or throw by the succeeding arms M attaining their respective limits of 95 projection until finally it is desired to return the controller-arm H, whereupon the operator on the car effects a rotation of cam-disk T, which effects a rocking of lever P, whereby the under edges of all the arms M 100 are engaged by the head O of such lever and raised out of engaging position with respect to abutment K, thereby permitting the weight of lever 7 or spring 8, as the case may be, to return the controller-arm to its initial or normal position.

The shaft L may be rotated in any suitable or convenient manner—as, for instance, through the intermeshing gears 10 and 11, respectively mounted on said shaft L and the 115 counter-shaft 9, suitably geared to the shaft of drum B, as clearly shown in Fig. 1.

From the foregoing description it will be seen that by using a number of eccentric or crank actuated arms M there will always be 120 at least one or more of the arms in proper position to engage behind abutment-surface K to start the controller-arm H in whatever position the shaft A, and hence also the motor-shaft, may be. It will also be seen that when 125 the said arm H attains the limit of its swinging motion by reason of the actuation of its initially-engaging arm, as above indicated, the other eccentric or crank actuated arms M coöperate with the first or initially-acting 130 eccentric-arm M to retain the controller-arm in that position—that is, as the first arm attains its limit of throw and begins to recede the next one to it is still advancing and en-

gages the abutment-surface, thus preventing the controller-arm from receding a sufficient distance from its extreme limit to allow it to break connection with the last contact of the 5 series G.

It will also be seen from the foregoing description that the controller-arm H may be actuated, if desired, from a controlled motor. The controller-arm is always driven in the 10 same direction whatever may be the direction of rotation of shaft L and hence in whatever direction the motor may operate. The power for effecting a rocking of controller-arm H is positive and practically unlimited, 15 which is a particular advantage over arms operated by solenoids, weights, frictions, or other devices capable of exerting only a comparatively limited or prescribed power. Therefore in case the contacts G offer any unusual 20 resistance to the passage therethrough and in contact therewith the said arm will nevertheless make its complete travel notwithstanding such conditions. The apparatus is purely mechanical, and hence avoids 25 the complexity of magnets or electrical devices and their circuits. No dash-pots are required, as the speed of throw for the controller-arm H is dependent upon the predetermined rate of rotation of the shaft L, the 30 throw of the eccentrics or crank connection, and the distance of the abutment-surfaces K from the axis about which the controller-arm H turns.

Having now set forth the object and nature 35 of our invention and a form of apparatus embodying the same and having set forth and described the construction, function, and mode of operation of such apparatus, what we claim as new and useful and of our own 40 invention, and desire to secure by Letters Patent of the United States, is—

1. In a controlling device for electric motors, a controller-arm, a rotatable shaft, a crank or eccentric actuated by said shaft and 45 arranged to loosely engage said arm, whereby when said crank or eccentric is projected said arm is positively moved in one direction, independent means for returning said arm, and means for rotating said shaft, as and for the 50 purpose set forth.

2. In a controlling device for electric motors, a controller-arm, a rotatable shaft, a plurality of arms having crank or eccentric connections with said shaft arranged to engage 55 said arms for actuating the same and means for rotating said shaft, as and for the purpose set forth.

3. In an apparatus of the class described, a controller-arm, a plurality of eccentric or 60 crank arms of varying periods of throw arranged to engage said controller-arm, means for actuating said crank or eccentric arms and

means for disengaging said arms from said controller-arm at will, as and for the purpose set forth. 65

4. In an apparatus of the class described, a controller-arm having an abutment-surface, a plurality of eccentric or crank arms of varying positions of eccentricity arranged to successively engage such abutment-surfaces 70 and means for actuating said arms, as and for the purpose set forth.

5. In an apparatus of the class described, a controller-arm having abutment-surfaces, a plurality of eccentric or crank arms of varying 75 positions of eccentricity arranged to engage said abutment-surfaces, means for actuating said arms and means for disengaging all of said arms simultaneously and at will from such abutment-surfaces, as and for the 80 purpose set forth.

6. In an apparatus of the class described, a movable controller-arm, means for normally maintaining said controller-arm in one limit of its movement, a series of eccentric or crank 85 arms of varying positions of eccentricity arranged to engage said arm, means for actuating said eccentric-arms and means for simultaneously disengaging all of said arms from said controller-arm at will, as and for 90 the purpose set forth.

7. In an apparatus of the class described, a shaft, means for rotating the same, a series of eccentrics of varying positions of eccentricity mounted thereon, a corresponding series of arms actuated by said eccentrics, a controller-arm arranged to be engaged by said eccentric-arms, a lever having a head arranged to simultaneously engage said eccentric-arms, and means for rocking said lever at will, 100 whereby all of said eccentric-arms are simultaneously disengaged from said controller-arm, as and for the purpose set forth. 95

8. In an apparatus of the class described, a shaft, means for rotating the same, a series 105 of eccentrics of varying positions of eccentricity mounted thereon, a corresponding series of eccentric-arms actuated by said eccentrics, a controller-arm arranged to be engaged by said eccentric-arms, a lever carrying a head arranged to simultaneously engage said eccentric-arms and to rock the same out of engaging position with respect to the controller-arm, and a rotatable cam-disk arranged to engage said lever to rock the same, 110 as and for the purpose set forth. 115

In witness whereof we have hereunto set our hands this 17th day of January, 1898.

THADDEUS W. HEERMANS.
NORMAN WHICELLO.
